UNITED STATES PATENT OFFICE.

MATTHEW F. BRAMLEY, OF CLEVELAND, OHIO.

SUBGRADE RUNWAY.

Application filed June 2, 1926, Serial No. 113,239. Renewed December 31, 1927.

My invention pertains to a sub-grade runway and more particularly to a detachably articulated series of duplicated structures comprising two parallel upwardly flanged 5 tracks for the passage of truck wheels.

My business of street paving has encountered a law requiring the use of sub-grade runways for the purpose of preventing the formation of ruts by the wheels of 10 vehicles which deliver the paving material along the course of the road way being built. The growing traffic of late years has made more and more important the fulfillment of the specifications as to thickness of the foundation for paved roads irrespective of the 15 upper surface material. If the trucks which deliver the road building material be permitted to cut up the surface of the sub-grade forming ground the consequent ruts 20 and ridges, if not re leveled, will, of course, result in a foundation, especially if indurated, which will be of non-uniform thickness and therefore of unequal supporting strength. It has been expected that 25 pavement contractors would relevel the sub-grade before applying the foundation there over, but that expectation has not always been satisfied and accordingly, unless a 30 check-up inspection was constantly maintained there could be no certainty that the progressive foundation was of substantial uniform thickness.

The object of my invention is to provide a runway over the sub-grade which will distribute the weight of delivery truck over an 35 area of sufficient breadth to prevent disruption of the sub-surface-grade. Another object is to provide a structure of duplicated assembly units which will facilitate their 40 transportation to and from a given job as well as their manipulation at a particular site so that the length of the runway may be progressively extended or shifted. A further object has been the design of sufficiently 45 economical units and which while adequately strong will be of minimum weight and the interconnection thereof so simple as to be obvious to an unskilled laborer.

I realize that the scope of my invention comprehends many equivalent methods and constructions. The showing of the drawings and the particular description are merely specific exemplifications of a plurality of 55 mechanical embodiments and arrangements.

Adverting to the drawings:

Figure 1 is an end elevation of my complete runway.

Figure 2 is an enlarged end view of one 60 duplicate side of Figure 1.

Figure 3 is a broken plan view showing the manner of effecting a dowel pin and 65 socket connection between the ends of two parts of the runway.

Figure 4 is a side view of a coupling element used in securing the end to end connection. 65

Figure 5 is a broken side elevation showing the manner of effecting another duplex 70 tongue and groove connection.

A duplicated series of wooden planks 1, preferably creosoted, carrying along their upper surfaces metal plates 2, attachment being accomplished by means of a plurality of bolts 3. The plates 2 are provided with short downwardly directed flanges 4 which 75 partially enclose the side edges of the planks and are also provided, along opposite longitudinal edges, with upwardly projecting flanges 5. The flanges 5 will be observed to 80 be of greater size and preferably diverge slightly as they proceed upwardly. One pair of corresponding ends of the flanges 5 are fashioned at the top as sockets 6, whereas the other pair of upper end portions of 85 the flanges 5 are fashioned as tenons 7, one of which is illustrated in Figure 5. The sockets 6 may be formed by looping the upper edges in the form of an eye in cross-section thereby incidentally reinforcing. 90 The tenon 7 may be secured in any appropriate manner in two corresponding ends of the socket 6, as for instance, by spot welding. It will be understood that the two tenons 7 will be so spaced and of a size to 95 fit in the sockets 6.

One end of each plank is confined within a U shaped channel iron 8, see Figure 3, having a pair of spaced openings which register with a pair of sockets 9 in the end 100 of the plank. The channels 8 are secured to the plank by a duplex eye bolt 10. The opposite end of each plank is enclosed within a U shaped channel iron 11 which carries a pair of dowel pins 12 adapted to occupy 105 the sockets 9. The channels 11 are similarly secured to the plank by duplex eye bolts 13. As will now be readily understood one end 110 of each plank is adapted for interlocking connection with a complementary end of another plank so that any number may be arranged into parallelly extending rows as

shown in Figure 1. After the dowel pins 12 occupy the sockets 9 clips or hooks 14 are employed having a pair of extremities 15 adapted to intersect the eyes 10^a and 13^a of the bolts 10 and 13 thereby maintaining the end to end connection. It is to be noticed that my end to end connection provides a duplex tongue and groove connection not only laterally, but in a direction from top to bottom.

The two parallel composite runways should, of course, be held a proper distance apart and for this purpose I provide the planks 1 at intervals with other bolts 16 having eyes 17 on the inner or opposed sides of the planks. Rods 18 of appropriate length are fashioned at each end with hooks 19 which intersect the eyes 17. The duplicated assembly units will permit of quick attachment and detachment and extension or curtailment of the length of the double runway to meet varying needs.

I claim:

1. In a sub-grade runway the combination of upwardly flanged structures arranged end to end and provided with a duplex tongue and socket connection.

2. In a sub-grade runway the combination of structures arranged end to end and provided with a duplex tongue and socket connection both laterally and in a direction from top to bottom, and means for maintaining the connections between said structures.

3. In a sub-grade runway the combination of a pair of structures arranged end to end and provided on each side with upwardly projecting flanges adapted near their tops for tongue and socket connection, another pair of structures similarly connected and spacer elements detachably connecting the sides of said endwise connected pairs of structures.

Signed by me, this 12 day of May, 1926.

MATTHEW F. BRAMLEY.
